UNITED STATES PATENT OFFICE.

JAMES F. HATHAWAY, OF SOMERVILLE, MASSACHUSETTS.

PICTURE-FRAME.

SPECIFICATION forming part of Letters Patent No. 619,743, dated February 21, 1899.

Application filed December 14, 1898. Serial No. 699,197. (No model.)

To all whom it may concern:

Be it known that I, JAMES F. HATHAWAY, of Somerville, in the county of Middlesex and State of Massachusetts, have invented a new 5 and useful Improvement in Picture-Frames, of which the following is a specification.

My invention relates especially to an ornamental casing adapted to receive and retain a picture-frame, so that the setting for the 10 picture may be varied at pleasure, and when in place in the casing the picture will be firmly held without danger of its falling out and yet may be easily removed, so as to be used without the casing.

15 My invention consists, mainly, in a casing of peculiar construction adapted to receive and firmly retain a picture-frame of the ordinary type having a hinged rest, whereby when removed from the casing it may be stood up 20 or hung, as desired, thus affording three methods of using said picture-frame.

My invention will be understood by reference to the drawings, in which the simplest method of utilizing my invention is shown.

25 Figure 1 shows the casing standing up in the ordinary manner with a picture contained therein, Fig. 2 being a rear view on an enlarged scale. Fig. 3 is a vertical section of the casing, the frame being shown in full. 30 Fig. 4 is a rear view of the casing with its back open, and Fig. 5 shows the picture-frame removed from the casing and standing in its ordinary position.

35 A represents the picture-frame with its suitable back and having a rest *a*, so that it may be stood upon a table, and also having for convenience an eye *a'*, so that it may be hung, if desired.

40 B is a casing, which is, in fact, a second frame, provided with a back *B'*, hinged, preferably, at the top and having a hinged rest *B''* attached thereto.

45 *b b* are cleats which are attached to the casing and may be turned to lock the hinged back *B'* in place.

C is a cross-bar which is within the casing, as shown in Fig. 3, its ends being firmly attached thereto.

In use the back *B'* of the casing is raised,

as shown in Fig. 4, and the frame is inserted 50 from the front, the rest *a* passing over the bar *C*, so that when the frame has been adjusted in place the rest *a* will hang down behind the bar, as shown in Figs. 3 and 4. The back *B'* being now closed and locked by the 55 cleats *b*, the frame will be retained in the casing by means of the engagement between the rest *a*, the rod *C*, and the back *B'* of the casing, which prevents the rest *a* from being drawn out over the rod *C*. To remove the picture, 60 the operation is reversed.

It will be seen that this structure is quite simple and yet may be made quite ornamental and serve to give variety to the setting of a picture, for the picture may be used in the 65 casing or it may be removed and stood up by itself, or by means of a cord attached to the ring *a'* (if the frame has such a ring) the picture may be hung to a curtain or a wall.

I have shown the part which passes behind 70 the bar *C* as a rest *a*; but it is evident that any hinged piece of suitable size will answer the locking purpose of this rest *a*.

It is evident that while I have shown a back *B'* as hinged it may be as well fastened to the 75 casing in some other way—for example, by means of two cleats at the top as well as two cleats at the bottom—instead of being hinged. Moreover, by “picture-frame” I mean to include not only such a frame as is shown in 80 the drawings, but any device for holding a picture which provides it with a back having a hinged portion which will be adapted to pass over a cross-bar and be retained in the casing in substantially the manner indicated 85 in the drawings.

The casing may be faced with cloth or leather or other suitable material, and the device taken as a whole affords a very effective and ornamental means for mounting a picture. 90

What I claim as my invention is—

1. The picture-frame casing above described having an opening in front to receive the picture-frame, a hinged back and a cross-bar located between said front and back, as 95 and for the purposes set forth.

2. The picture-frame casing above described having an opening in front to receive

the picture-frame and a hinged back provided with a rest and a cross-bar located between said front and back, as set forth.

3. The picture-setting above described consisting of an inner frame provided with a hinged piece and a casing having a front opening to receive said frame and a rear opening having a back, said casing being provided

with a cross-bar between said front and back, as set forth. 10

In witness whereof I have hereunto set my name this 10th day of December, 1898.

JAMES F. HATHAWAY.
